Fig. 11.

Fig. 12.

FIG. 1 is a front elevational view of a light standard or similar article showing my new design;

FIG. 2 is a cross-sectional view taken on line 2—2 of FIG. 1;

FIGS. 3 and 4 are enlarged cross-sectional views taken on lines 3—3 and 4—4 respectively of FIG. 1;

FIGS. 5 and 6 are enlarged cross-sectional views of a second embodiment of my design taken on planes identical to lines 3—3 and 4—4 respectively of FIG. 1, it being understood that the second embodiment differs from FIG. 1 only in cross-section;

FIGS. 7 and 8 are enlarged cross-sectional views of a third embodiment of my design taken on planes identical to lines 3—3 and 4—4 respectively of FIG. 1, it being understood that the third embodiment differs from FIG. 1 only in cross section;

FIGS. 9 and 10 are enlarged cross-sectional views of a fourth embodiment of my design taken on planes identical to lines 3—3 and 4—4 respectively of FIG. 1, it being understood that the fourth embodiment differs from FIG. 1 only in cross-section;

FIG. 11 is a front elevational view of a fifth embodiment of my design, the standard being broken away for convenience of illustration;

FIG. 12 is a top plan view thereof.

The lamps are shown in broken lines in FIGS. 1—2 and 11—12 for illustrative purposes only.

I claim:

The ornamental design for a light standard or similar article, as shown and described.
